UNITED STATES PATENT OFFICE.

JOHN A. EASTIN, OF ST. LOUIS, MISSOURI, ASSIGNOR OF ONE-HALF TO JOHN R. WILLIAMS, OF SAME PLACE.

PAPER-CUTTER.

SPECIFICATION forming part of Letters Patent No. 394,476, dated December 11, 1888.

Application filed February 9, 1888. Serial No. 263,456. (No model.)

To all whom it may concern:

Be it known that I, JOHN A. EASTIN, of the city of St. Louis, in the State of Missouri, have invented a certain new and useful Improvement 5 in Paper-Cutters, of which the following is a full, clear, and exact description, reference being had to the accompanying drawings, forming part of this specification, and in which—

10 Figure I is a front view in elevation of my paper-cutter, with part broken away to show the bevel-slotway through which the paper is drawn for a recut and broken away on another part to show the tension-spring. Fig. II 15 is an end view in elevation showing the action of the spring tension-arm on the roll and the position of the forward edge of the paper ready for grasping for drawing out preparatory to cutting; and Fig. III is a vertical section taken on line III III, Fig. I, showing the course of the paper over the friction-roller, through the bevel inclined slot, and raised in contact with the knife ready for cutting.

15 This invention relates to devices for combined portable and stationary paper-cutters with stationary knives; and the invention consists in features of novelty hereinafter fully described, and pointed out in the claims.

20 Referring to the drawings, in which similar figures of reference indicate like parts in all the views, 1 represents the base, 2 the posts, and 3 the cap, of the frame in, and in connection with, which my paper-cutter is worked. The foot-flanges 4 of the posts are fastened to 25 the base by screw-bolts 5, and the cap-piece to the head of the frame or posts by screw-bolts 6.

25 7 is the rotary shaft, and 8 its spindles, which have bearings 9 between the projecting lugs 10 and 11 on the rear edges of the posts.

30 12 are the spools which carry the paper roll 13, and are preferably made sectional, passing in and only part of the way through the paper roll; but they may, if preferred, be made integral the whole length of the roll.

35 14 represents the upwardly-extending tension-bar, which is provided with an elongated T-head, 15, which projects at both ends beyond the stems that carry it, and horizontal 40 pivotal feet 16, that proceed at a right angle outwardly from said stem to the same extent as the outward projections of the T-head. The said feet have bearings within the eyelet-

bolts 17, which are secured within the boxings 18 within the base of the frame. Tension-springs 19, whose initial ends are clasped around the outer eyelet-bolts, coil around the foot-sections of the tension-bar, and have projected arms 20, that are elevated above the base, embrace the stems of the tension-bar, 55 and enforce the spring-tension of its T-head against the paper roll. It will be seen that the feet of said tension-bar are seated in their boxings in the base in the front of the frame, and, passing under the roll, exert their tension 60 under and upwardly against its rear side, and so, contrary to the usual device in paper-cutters, applies its spring-tension at a point remote from that at which the paper is cut, so as not to antagonize or interfere with the operation of the knife.

21 represents a friction-roller, whose spindles 22 have bearings 23 formed on the lugs 24, that project from the rear of the posts near the top of the same. The loose end of the 75 paper from the roll passes over the said friction-roller at a right elevation to carry it preferably at a slight incline from said roller to the upper edge of the curve-faced bar 25, the angle-flanges 26 of which are firmly secured to the inside of the posts near the top 80 of the same by screws or bolts 27. The loose end of the paper, after passing over the corner of said curve-faced bar, passes down and out between the face of said bar and around 85 edged bar 28, which is pivotally secured by the bolt 29 to the front cross-bar, 30, that enforces the connection of the tops of the posts, and at its loose end is fastened by a thumb-screw, 31. When the thumb-screw is unseated, the bar 28 may be lowered at its then loose end, turning on its pivot-bolt 29 to give more free movement to the hand in reaching through for the initial insertion of the loose end of the paper when a fresh roll is placed in 90 the frame. To further facilitate access to the hand of the operator, the connecting-bar 30 may, if desired, be arched or curved upward from the posts.

32 represents the knife, which is stationary 100 and firmly secured to the bevel edge 33 of the cap of the frame by screw-bolts 34. The edge of the knife is beveled outward, so as to locate its cutting-edge in the most favorable position for severing the paper when it is elevated for so doing.

It will be seen that by having the knife removed from the roll, which is ever varying in diameter as the paper is used, I avoid the objectionable feature of a loose adjustable 5 knife, which, of necessity, has a give-and-take movement that results in an uneven tear of the paper, and also insure other advantages that will be referred to in the operative description.

10 The spring tension-bar, it will be seen, has its pivotal foot hold and spring attachment in boxings in the front of the base, and, unlike the usual position of tension-arms, it curves from said position upwardly under and to the 15 rear of the roll at a point about the most remote from the point of severance of the paper. By this arrangement the first tension and cutting features of the device are removed from all antagonistic interference with 20 each other. Another feature of said spring tension-bar is its T-arms, that extend out laterally from the stem to the out edges of the roll. This avoids the difficulty experienced by the usual form of tension-bars, which have 25 not said lateral extensions of the T-arms, but proceeding direct from their stems, their tension is not uniform, but is exerted too much on the extreme edges, while the bar gives outwardly in the middle and is in danger 30 of resulting in a tension tear at the edges.

The operation of the device is as follows: The paper roll, having had its shaft and sectional spools inserted, is placed on its bearings in the frame. The forward edge, 35, of 35 the paper is then placed over the friction-roller 21 and through the curved slotway that is formed by the curve-faced bar 25 and the round-edged bar 28. To facilitate the process, the thumb-screw 31, that fastens one end of 40 the bar 28, may be loosened and said bar turned down on its pivotal connection at the other end. Then, especially if the cross-bar 30 is arched, there will be provided more convenient room for the placement of the 45 paper. The bar 28 having been readjusted in its place and the thumb-screw seated, it will be seen, as shown in all the views, the front edge, 35, of the paper projects outward and forward, so as to present an easy catch- 50 hold for drawing a sufficient length of the paper forward, according to size of the piece required.

In drawing the paper preparatory to cutting it should be drawn downward and 55 slightly forward, so as to pass through the curved slot free of almost all friction. The forward edge of the paper is then raised, so as to bring the part to be severed in contact with the edge of the knife.

60 It will be seen that when the paper is lifted in contact with the knife it immediately enforces a second tension at the outlet of the curved slot against the round-edged tension-bar 28, causing a sufficiently rigid tension to 65 firmly hold the paper at that point while being cut, thus preventing the injurious feature of dragging during the process of cutting, and

thus making a ragged tear; also, the knife not being adjustable, as all have to be that work against the roll, but rigidly secured to the 70 bevel edge of the cap where there cannot be any give-and-take movement of the knife, (as of necessity there must be with adjustable knives;) a clean cut can invariably be secured.

75

I claim as my invention—

1. In a paper-cutter, the combination of the paper roll, the spring tension-bar pressing against the lower rear portion of the roll, the curved bar 25, and second tension-bar, 28, substantially as and for the purpose described.

80

2. In a paper-cutter, the combination of the paper roll, the upwardly-extending spring tension-bar pressing against the lower rear portion of the roll, the curved bar 25, second tension-bar, 28, and the knife 32, the second tension-bar being remote from the knife, substantially as and for the purpose set forth.

85

3. In a paper-cutter, the combination of the paper roll, the frame in which it is hung, and the upwardly-extending spring tension-bar beneath the roll, the laterally-extending T-arms of said bar arranged to equalize the tension on the roll, substantially as and for the purpose set forth.

90

4. In a paper-cutter, the combination of the paper roll, the frame in which it is hung, the T-shaped spring tension-bar, the horizontal feet of said bar, the boxings in the base of the frame in which said feet have their pivotal bearings, the tension-springs 19, that enforce said bar, the second tension-bar, 28, and stationary knife 32, the first tension-bar arranged to exert its pressure at a line remote from the knife and the second tension-bar remote from the roll, substantially as and for the purpose set forth.

95

5. In a paper-cutter, the combination of the frame, paper roll, the spring-tension having pressure on the roll at a line remote from the knife, and the pivoted second tension-bar and thumb-screw that secures it, the said bar exerting its tension on a line remote from the roll and adjacent to the knife, for the cut of which it holds the paper in rigid tension, and the stationary knife rigidly secured to the bevel front edge of the cap of the frame, and thus held to its work to effect a clean cut, substantially as and for the purpose set forth.

100

6. In a paper-cutter, the spring T-shaped tension-bar that exerts its pressure on a line remote from the knife, the friction-roller 21, and second tension-bar with tension on a line remote from the paper roll, and the stationary knife, sufficiently removed from the second tension-bar to provide a suitable catch-hold of the forward edge of the paper after severance for a redraw and recut, substantially as and for the purpose set forth.
